DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW JERSEY.

CASTING-CONTROL MECHANISM FOR TYPOGRAPHIC MACHINES.

1,280,077.

Specification of Letters Patent. Patented Sept. 24, 1918.

Application filed December 4, 1915. Serial No. 64,985.

To all whom it may concern:

Be it known that I, DAVID PETRI-PALMEDO, a citizen of the United States, residing at Bridgeport, in the county of Fairfield and State of Connecticut, have invented a certain new and useful Improvement in Casting-Control Mechanism for Typographic Machines, of which the following is a full, clear, and exact description.

10 This invention relates to circulating-matrix line-casting typographic machines. The object of the invention is to endow a machine of this character with two desirable qualities, viz: the capacity for rejecting an 15 assembled line of matrices and spaces, that is to say, for delivering said matrices and spaces to the distributing mechanism by which they are returned to their respective magazines without casting a slug therefrom; 20 and the capacity for casting any desired plural number of slugs from the same assembled line of matrices and spaces.

To accomplish these desirable results certain changes have been made in and certain 25 things added to mechanisms which have heretofore been used for causing the properly synchronized sequential operation of the mechanisms by which an assembled line of matrices and spaces is justified and 30 clamped, and a slug cast therefrom, and the matrices and spaces thereafter separated and delivered, the former to the matrix distributing mechanism and the latter to the spacer magazines. But these changes and 35 additions are of such character that they do not interfere with the normal functioning of this mechanism in order that a line of matrices and spaces may be justified and a single slug cast therefrom and said line delivered to the line disintegrating and 40 distributing mechanism; but they do provide for operating this mechanism abnormally to produce the results desired.

The invention is exemplified in connection 45 with certain known mechanisms, and is shown in the drawing and hereinafter described and pointed out definitely in the appended claims.

In the drawing, Figure 1 is a front elevation of so much of the mechanism of a typographic machine of the character specified as is necessary for the understanding of the present invention; Fig. 2 is a side elevation of the first elevator and some associated 55 parts, particularly the means whereby said

elevator as it goes up may or may not cause the line withdrawing mechanism to operate; Fig. 3 is a sectional view in the plane of line 3-3 on Fig. 1, Fig. 4 is a sectional rear view of so much of the mechanism of a typographic machine of this character as it is necessary to show; Fig. 5 is a sectional side elevation of the mechanism shown in Fig. 4; Fig. 6 is a development of the clutch sleeve, and Fig. 7 is a longitudinal sectional view of said sleeve showing it and the pins which control its position in a different position from that which is shown in Fig. 5.

Referring to the parts by reference characters, 10 represents the casting control cam shaft; 12 represents that one of the cams thereon which controls the operation of the metal pump piston. This cam shaft 10 is the shaft on which, commonly, in machines 70 of this character there are numerous other cams which cause or control the operation of various parts having to do with the justification and clamping of the matrix line, the presentation of the line to the mold, the 75 discharge of molten metal into the mold and movements of the so-called first elevator, as heretofore set forth. 13 is a gear fixed to this cam shaft, 14 a pinion which meshes with this gear and with a gear 15, that is 80 loosely mounted on a constantly rotating shaft 16. The pinion 14 may be mounted on a constantly rotating shaft 17 on which is a gear 18 that meshes with the gear 19, which gear is fixed to the shaft 16 and to a 85 ratchet wheel 20.

Mounted on the gear 15 is a rock shaft 21 to which a pawl 22 is fixed, which pawl is adapted to engage with the ratchet wheel 20, and thereby effect a driving connection 90 between it and the gear 15. Fixed to the rock shaft 21 is an arm 23 to which arm a spring 24 is fastened, so as to exert upon the rock shaft 21 a force tending to rock it, and thereby carry the pawl 22 into engagement with 100 the ratchet 20. A casting control lever 25 is pivoted to the frame work of the machine in a position such that as the gear 15 is turning in the direction of the arrow thereon in Fig. 5, the arm 23 will come into contact 105 with the end of said lever 25, whereby the rock shaft 21 will be rocked and the pawl 22 withdrawn from its engagement with the ratchet 20. The gear 15 being thereby disconnected from the ratchet 20 will stop, and 110

so will also the cam shaft 10. If, however, one should rock the lever 25 out of engagement with the arm 23, the pawl 22 will fly into engagement with the ratchet 20 and thereupon the gear 15 will begin to rotate, and, through the described intermediate mechanism, will rotate the casting control cam shaft 10.

All of the foregoing mechanism is old in some form or another. Ordinarily there is a so-called line key, and mechanism by which when the line key is depressed, the lever 25 will be rocked out of engagement with the arm 23, thereby causing this casting control cam shaft to begin its operation. Usually also this lever 25 will be automatically returned to its operative position before the gear 15 completes its single revolution, wherefore when said revolution is completed the arm 23 will again engage with the lever 25, with the final result before stated of causing the cam shaft 10 to stop rotating.

A bell crank lever having two arms 27, 28, 29 is mounted to rock on the shaft 17. The arm 27 carries a roller 27 which engages the surface of the metal pump-controlling cam 12. The other arm 28 is connected by a link 29 with a rocking lever 30. This lever is under the influence of a spring 31 tending to draw its free end downward. The metal pump piston 32 is connected by a connecting rod 33 with this lever 30. It will be seen, therefore, that the high part of the cam 12 by engaging with the lever arm 27 will, through the described mechanism, prevent the spring 31 from so rocking the lever 30 as to cause the metal ejecting downward movement of the metal pump piston 32. When, however, the cam 12 in its rotation brings a low part of said cam under the roller 27, the spring 31 will then be free to act, and will suddenly move lever 30 down, and so cause the metal ejecting movement of the metal pump piston. This is likewise old mechanism in machines of this character.

40 represents the so-called first elevator, which is mounted for vertical movement on the frame work of the machine. It is constructed to hold a line of matrices and spaces. It normally occupies a position such that the assembled line can be moved onto it from the assembly rails; and then it is moved down to a position such that the matrix line supported thereby can be clamped and justified and made to close one side of the mold slot whose other side is closed by the pot nozzle. This elevator may be moved up and down by the means shown in Fig. 1, that is to say, the downwardly extended tail piece 41 of the elevator may be formed with rack teeth 42, and a pinion 43 fixed to a shaft 44 may engage with these rack teeth. Another pinion 45 fixed to this same shaft affords the means 46 for turning the shaft first in one direction

and then in the other by known means whose action is controlled by a cam on the cam shaft 10 in the usual way.

This elevator after it has presented the matrix line to the mold goes up to a position where, as before stated, this matrix line is removed from the elevator. In a fixed box 50 there is mechanism for this purpose substantially like that which is shown and described in my prior application, No. 868,175; that is to say, it is like said mechanism except for a few changes and additions which will be explained. This mechanism is normally inactive. It includes a clutch 60 by means of which the main shaft of this mechanism 65 may be connected with a constantly rotating worm wheel 66. This clutch is a jaw clutch, and it is under the influence of a spring 61 tending to move it into engagement with the rotating worm wheel 66. It has in its surface two circumferentially extended cam grooves 62, 63. This is one of the points of difference between this sleeve and that shown in said prior application, which had only one of these cam grooves. 66^a represents a pin adapted to enter the groove 63 and by engaging with the inclined wall 63^a of the groove 63 to cause the movement of this clutch sleeve to the unclutching position. This pin 66^a is also new. 67 represents a pin which is adapted to engage the groove 62 and by engaging with the inclined wall 62^a thereof to withdraw the clutch sleeve to the unclutched position. Fig. 6 shows the relation of these two grooves to each other. In this box is a rock shaft 70 having two arms 71, 72, the latter being located outside of and in front of the box and in a position such that the trip pin 49 carried by the elevator may engage with it and trip it when the elevator reaches the top of its path. This pin 67 and the mechanism in the box for operating it is old, and so also is a tripping device carried by the elevator to operate in the manner stated.

The pin 66^a is engaged by a lever 80, which is connected by a link 81 with one arm 82 fixed to a rock shaft 83, to which also another arm 84 is fixed, which arm 84 engages a plunger 86 that in turn engages with the rear end of a key lever 85.

Coming back to the mechanism in the line transfer box 50, it will be noted that there is a cam 75 fixed to the shaft 65. A lever 76 engages the surface of this cam and normally engages with the high part 75^a thereof. This lever is connected by a link 77 with an arm 78^a that is fixed to a rock shaft 78, said rock shaft carrying another arm 78^b, which is connected by a link 79 with the stop lever 25.

The pump piston operating lever 30 is fixed to a rock shaft 90 to which also an arm 91 is fixed. This arm 91 engages with the top of a pump preventer plunger 92

which is normally under the influence of a spring 93 tending to raise it to its uppermost position. This plunger is mounted in a suitable bearing 94 therefor, and it is formed with a hole 95 in its side. A dog 96 in the form of a pin sliding in the bearing 94 is provided, and is arranged so that it may enter the hole 95 and therefore prevent the plunger 92 from going down. A line rejecting key 100 is fixed to a rock shaft 101 to which also is fixed an arm 102 that engages with the dog 96. A rearwardly projecting arm 103 fixed to rock shaft 101 engages beneath the end of an arm 103 which is fixed to the rock shaft 83.

The normal operation of the machine, that is to say, the operation of a machine when it is desired to cast a single slug from an assembled line, is substantially as follows: The operator depresses the line key 85, and thereby through the train of mechanism described, beginning with the plunger 86, he causes the pin 66^a to be withdrawn from the groove 63 in the clutch sleeve 60. Thereupon this clutch connects the shaft 65 with the driving mechanism, and said shaft begins to turn. Very soon after it has so begun to turn the high part of the cam 75 passes from beneath the lever 76 whereupon the spring 25^a is free to and does so rock lever 25 about to withdraw its end from its engagement with the lever 28. Thereupon the pawl 22 will engage with the ratchet 20 which causes the casting control cam shaft 10 to be connected with its driving mechanism and said shaft begins to turn, with the result of causing the proper sequential movement of all of the mechanisms whose movements are caused or controlled by cams on said cam shaft. Almost as soon as the high part of the cam 75 has passed from beneath the lever 76 the inclined part 62^a of the groove 62 in the clutch sleeve 60 will engage the upper pin 67, and thereby said clutch sleeve will be moved in the unclutching direction, and thereupon the shaft 65, and all the mechanism in the box 50 operated thereby will stop. In the course of time, and as the cam shaft 10 performs its functions, which will include the casting of a slug from the assembled line of matrices on the elevator, the elevator will go up, the trip pin 49 thereon will engage the lever 72, and thereby withdraw the pin 67 from the groove 62 in the clutch sleeve 60. This sleeve will now clutch shaft 65 to the driver 66^a, and said shaft 65 and all the mechanism operated thereby will again begin to operate. As before stated, this mechanism is substantially like that shown in my prior application, and the result of so operating this mechanism will be to withdraw the matrix line from the elevator and carry it to the embrace of the line disintegrating mechanism. When the shaft 65 has

completed the second part of its single revolution the high part of the cam 75 will have passed under the lever 76, and thereby through the described intermediate mechanism the stop lever 25 will be brought into the path of the arm 28 and thereby, as before stated, the pawl 22 will be moved out of engagement with the ratchet 20, and therefore the cam shaft 10 will stop. It is to be remembered, however, that in the meantime the elevator has been by the cam shaft moved down to its starting point. The stopping of the shaft 65 when it has completed its single revolution will be brought about by the engagement of the pin 66^a with the inclined part 63^a of the groove 63, the immediate result being the withdrawal of the clutch sleeve from its clutching position.

If, however, the operator has made so many mistakes in assembling a line that he does not wish to cast a slug from it, he will then instead of depressing the line key depress the line rejecting key 100. By so doing he will rock the rock shaft 83 and produce precisely the same results before explained, as would have been produced had the line key 85 been depressed. But he will do more, that is to say, he will rock the rock shaft 101 and so that the arm 102 carried thereby will push the dog 96 into hole 95, and thereby prevent the descent of the pump preventer plunger 92. Inasmuch as the depression of this key 100 did do precisely what the depression of the line key 85 would have done, it follows that through the operation of the mechanism already described the cam shaft 10 will have been set in operation, whereby the cams thereon will cause and control the operations of all of the mechanisms having to do with the casting of the line. But when the high part of the cam 12 passes under the roller 27^a so as to thereby release the pump piston operating lever 30 to the influence of the spring, said lever cannot move because if it moves the rock shaft 90 would have to rock, and this is prevented by the engagement of the arm 91 thereon with the now immovable pump preventer plunger. Therefore, all of the usual mechanism in the machine will operate in the usual way excepting only that the metal pump plunger is not permitted to be moved by its spring in the metal ejecting direction.

Fixed to the elevator 40 is a cam plate 48. Fixed to the rock shaft 101 is an arm 104 having a friction roller 104^a mounted in its end in a position such that as the elevator moves upward above its normal position, as it does after the casting mechanism has operated, this cam plate 48 will engage the arm 104 and so rock the shaft 101 as to withdraw the dog 96 from its engagement with the pump preventer plunger 180.

92, and therefore all obstacles to the normal operation of the metal pump piston when another line has been put upon the elevator will be removed.

5. The trip pin 49 carried by the elevator goes horizontally through the elevator and has an operating knob 49^a fixed to its front end. It fits sufficiently tight in the hole through which it passes that it will remain in any position to which it is moved, and normally it projects rearward so far that as the elevator goes up it will trip the lever 72 and so set in operation the mechanism which withdraws the line from the elevator and which also causes lever 25 to move into the operative position with respect to arm 23. If, now, the operator wishes to cast a plurality of lines from a single matrix line he first pulls the trip pin 49 forward, thereby 15 withdraws the rear end of said pin into the elevator so that as the elevator goes up this pin cannot engage lever 72, and therefore cannot trip the line transfer mechanism and cause it to go through the second part of its 20 cycle.

The mechanism in the box has however gone through the first part of its cycle, and therefore the cam 75 is in the position such that through the mechanism described the lever 25 is moved to the inoperative position. It is only moved to the operative position by that movement of cam 75 which takes place when the line transfer mechanism has gone through the second part of its cycle. Therefore, since the trip pin cannot engage lever 72, the up and down movement of the elevator will not withdraw pin 67 from its engagement with the clutch, and therefore there is nothing to start this line transfer 35 mechanism in operation. The cam shaft 10, therefore, continues to rotate indefinitely, and in rotation will carry the elevator up and down with the matrix line thereon, because said line has not been removed from 40 the elevator, and it will likewise cause the clamping and justification of the line and the casting of a slug therefrom time after time, and until the operator having enough slugs cast pushes the stop pin rearward, so 45 that in the next excursion of the elevator upward this trip pin 49 will engage the lever 72 and therefore withdraw pin 67 from its engagement with the clutch sleeve, so that as a result the line transfer mechanism can 50 go through the second half of its cycle, during which as stated the line is withdrawn from the elevator and the stop lever 25 moved into the position such that by engaging the arm 23 it will cause the cam shaft 10 55 to stop.

Having described my invention, I claim:

1. In a typographic machine of the character specified, in combination, with a normally idle casting control cam shaft, means 60 for connecting said cam shaft with the driving

mechanism therefor, a metal pump, a spring to actuate said metal pump in the metal ejecting direction, and a cam on said cam shaft for preventing the spring induced action of said pump, of means independent of said cam to prevent the spring induced action of said metal pump, a line rejecting key, and mechanism operable thereby to cause the connection of said cam shaft with its operating mechanism and to render operative the independent means for preventing the metal ejecting operation of the metal pump.

2. In a typographic machine of the character specified, in combination with a normally idle casting control cam shaft, means for connecting said cam shaft with the driving mechanism therefor, a metal pump, a spring to actuate said metal pump in the metal ejecting direction, and a cam on said cam shaft for preventing the spring induced action of said pump, of means independent of said cam to prevent the spring induced action of said metal pump, a line rejecting key, mechanism operable thereby to cause the connection of said cam shaft with its operating mechanism and to render operative the independent means for preventing the metal ejecting operation of the metal pump, the first elevator, and means carried thereby 95 to render inoperative the independent pump restraining means.

3. In a typographic machine of the character specified, the combination of a metal pump, a rock shaft, an arm secured thereto, a connecting rod connecting said lever with the metal pump piston, a spring operating to move said metal pump piston in the metal ejecting direction, a second arm connected with said rock shaft, a pump preventer plunger engaging the latter arm, a line rejecting key, mechanism rendered operative by said key to release said pump piston to the action of its operating spring, and means also operable by said line rejecting key for 100 engaging with and preventing that action of the pump preventer plunger which must necessarily accompany the metal ejecting movement of the metal pump piston.

4. In a typographic machine, the combination of the metal pump, its piston, a spring for actuating the piston in the metal ejecting direction, means normally restraining said pump piston from so acting, a device which must move when the pump piston moves in 105 the metal ejecting direction, a pump preventer plunger which lies in the path of said device, a line rejecting key, means operable by said key for releasing the pump piston from the normal restraining means, a rock 110 shaft to which said key is connected, a dog adapted to engage and restrain the movement of the pump preventer plunger, an arm fixed to said rock shaft engaging said dog, the vertically movable first elevator, a cam 115

block fixed thereto, and an arm fixed to the same rock shaft to which the line rejecting key is fixed which arm projects into the path of and is adapted to be operated by said cam block.

5. In a typographic machine of the character specified, the combination of the metal pump, a spring for actuating it in the metal ejecting direction, a rotatable cam restraining the spring induced movement of said metal pump, a device wholly independent of said cam normally occupying an inoperative position but capable of occupying an operative position in which it will prevent the 10 spring induced movement of said metal pump, a line rejecting key, and mechanisms rendered active thereby for turning said cam and for moving said independent restraining device into operative position in which 15 it will prevent the spring induced movement of the metal pump when restraining influence of said cam is withdrawn by the rotation of said cam.

6. In a typographic machine of the character specified, the combination of the metal pump, a spring for actuating it in the metal ejecting direction, a rotatable cam restraining the spring induced movement of said metal pump, a device wholly independent of 20 said cam normally occupying an inoperative position but capable of occupying an operative position in which it will prevent the spring induced movement of said metal pump, a line rejecting key, and mechanisms rendered active thereby for turning said cam and for moving said independent restraining device into operative position in which 25 it will prevent the spring induced movement of the metal pump when the restraining influence of said cam is withdrawn by the rotation of said cam, the vertically movable first elevator and means carried thereby for restoring said independent restraining device to its inactive position.

45. 7. In a typographic machine of the character specified, the combination of a casting control cam shaft, a cam thereon, a clutch device for connecting said cam shaft with the driving mechanism therefor, a metal 50 pump and its piston, a spring for moving said piston in the metal ejecting direction, mechanism controlled by said cam for preventing such spring induced movement, the vertically movable first elevator, mechanism for withdrawing a matrix line from said 55 first elevator which mechanism is normally inactive, an automatic clutch having a sleeve containing two cam grooves, and adapted to render said line withdrawing means active, 60 two pins adapted to respectively enter said two cam grooves and thereby to withdraw the clutch from action, a key, mechanism operable by said key for withdrawing one of said pins from action, a cam fixed to a 65 rotatable part of said line withdrawing

mechanism, a lever engaging said cam, a train of mechanism operable by said lever to control the position of the casting control cam shaft clutch, the vertically movable first elevator, an adjustable trip device thereon, a 70 train of mechanism through which the other pin is withdrawn from the other cam groove in said clutch sleeve, a part of said mechanism being located in the path of said trip device when the latter is projected into operative 75 position.

8. The combination of a normally inactive casting control cam shaft, a vertically movable first elevator, normally inactive mechanism for withdrawing a matrix line from 80 the elevator, a cam which turns synchronously with the movement of said line withdrawing mechanism, means controlled by said cam for connecting and disconnecting the cam shaft from a source of power, a key, 85 means operable thereby for connecting the line withdrawing mechanism with a source of power, means acting automatically to stop said line withdrawing mechanism before it has completed its cycle, a tripping device for 90 withdrawing said stopping means and again permitting the line withdrawing mechanism to operate, and a movable device carried by the first elevator and capable of occupying positions in which it will or will not engage 95 said tripping device.

9. In a circulating matrix line casting typographic machine, the combination of a normally idle casting control cam shaft, a vertically movable first elevator adapted to 100 support an assembled matrix line, a normally idle rotatable cam, means controlled by said cam to connect and disconnect said cam shaft and a source of power, a key, 105 means controlled by said key for connecting the said cam with a source of power, an automatically acting device for disconnecting said cam from said source of power before the cam has completed one complete revolution, a tripping device movably 110 mounted on the first elevator and adapted to occupy an operative and inoperative position at will, a lever which extends into the path of said tripping device when the latter is in operative position, and mechanism 115 operable by said lever for again causing said cam to be connected with the source of power.

10. In a circulating matrix line casting typographic machine, the combination of a 120 normally idle casting control cam shaft, a vertically movable first elevator adapted to support an assembled matrix line, a normally idle rotatable cam, an automatic clutch for connecting said cam with a source of 125 power, two devices which act automatically to withdraw said clutch at different times in the revolution of said cam, means controlled by said cam to connect and disconnect the cam shaft and a source of power, 130

a key, means controlled by said key for withdrawing one of said clutch restraining devices, a tripping device mounted on the first elevator and adapted to occupy an operative or an inoperative position, a lever which extends into the path of said tripping device when the latter is in operative position, and mechanism operable by said lever

for withdrawing the second clutch restraining device.

In testimony whereof, I hereunto affix my signature in the presence of two witnesses.

DAVID PETRI-PALMEDO.
